ELECTRIC LIGHTING FIXTURE

Earl S. Boynton, East Orange, N. J.

Application October 10, 1938, Serial No. 234,125

7 Claims. (Cl. 240—81)

This invention relates to electric lighting fixtures, and particularly to lighting fixtures such as reading lamps or the like.

It is an object of the present invention to provide a lighting fixture embodying means whereby the lamp means thereof may be lighted or extinguished by suitable rotation of the lamp shade.

It is another object of the invention to provide a lighting fixture of the type described, in which switch means controlling the operation of a plurality of electric lamps, or controlling a plurality of electric circuits serving a single lamp, may be selectively operated by pressure exerted on the lamp shade.

Further, it is an object of the present invention to provide an electric lighting fixture in which the electric switch means may be entirely concealed, operation of said switch means being effected by displacement of the lamp shade about a fixed pivot point.

In this invention, the lamp may comprise a base of suitable material, said base desirably being hollow and serving to receive, and rigidly mount, lamp socket means and switch means for said socket means.

Disposed in suitable operative relationship to said lamp socket means and said switch means there is provided a fixed standard affording means for pivotally, i. e., rotatably, mounting a lamp shade. The switch means may be of any standard type; in simplification of the present invention, however, the switch means are desirably of the double action plunger type, in which a spring-biased plunger actuates a rotating electric contact mechanism to close the electrical circuit during one movement of the plunger, and to open said circuit on a succeeding movement.

In one form of the present invention, the switch means are disposed in suitable fixed relationship with respect to the base, and in a manner which disposes the plunger elements thereof operably adjacent suitable bearing surfaces of the lamp shade. In such arrangement, the pressure of the hand at one end of the lamp shade will cause a rotation of said shade about its pivot, moving the bearing surface of the shade against the switch plunger means to operate its associated lamp switch.

In a second embodiment of the invention, lamp switch means may be entirely concealed within the base of the lighting fixture. In such embodiment, the lamp shade may be provided with rotatable means disposed in part within the space occupied by said switch means and in suitable operative relationship to the switch actu-

ating plungers. As later described in detail, displacement of the shade about its pivot is effective to move such rotatable element in one or another direction, selectively operating the switch means.

It is a feature of the present invention, therefore, that displacement of a lamp shade about a supporting member serves to actuate one or more lamp switch elements, said switch elements serving positively to return said lamp shade to normal position.

Other features and advantages will hereinafter appear.

In the accompanying drawing:

15 Fig. 1 is an elevation of a lighting fixture, pursuant to the present invention;

Fig. 2 is a plan view of the lighting fixture of Fig. 1;

Fig. 3 is an enlarged sectional elevation, taken 20 along the lines 3—3 of Fig. 2, particularizing a method of pivotally mounting the lamp shade with respect to the switch means, and illustrating further a type of switch suitable for the present invention;

25 Fig. 4 is a typical wiring diagram for the lighting fixture;

Fig. 5 is a side elevation, partly in section, of a second arrangement of switch means and the actuating means therefor;

30 Fig. 6 is a sectional elevation of the embodiment of Fig. 5; and

Fig. 7 is a fragmentary sectional elevation of a third means for rotatably mounting the lamp shade.

35 Referring to the drawing, an electric lighting fixture 10, hereinafter referred to as a lamp, comprises a base 11, a lamp shade 12 suitably positioned with respect thereto, lamp socket means 13, 13 for the reception of suitable electric bulbs 14, 14, and switch means 15, 15. In the embodiment shown, a switch is provided for each of said electric bulbs.

40 Preferably, see Fig. 3, the base 11 is of hollow construction, and provided with a bottom closure plate 16. The lamp sockets 13, 13, may be of conventional design; as illustrated, a threaded neck 17 thereof extends through a suitable opening in the surface of the base 11. The socket may be rigidly secured to the base by suitable lock nut means 18. A suitable washer 19 protects the surface of the base 11 when securing the said sockets.

45 The electric switches 15, 15 may be of any standard form; however, switches of the rotating contact type, in which the rotation of a

screw member 21 serves to rotate suitable switch elements (not shown) to successively make and break the electric circuit, are preferred. In the type of switch illustrated, the rotation of screw member 21 is effected by the displacement of a cooperatively threaded plate 22 secured to the bottom of the switch plunger 23. As indicated, the plunger 23 may have a hollow interior, housing a coil spring 24, confined between the upper wall portion of the plunger 23 and a suitable bearing plate 25 secured to the upper end of the screw element 21.

In such a switch, the rotation of screw 21 during the downward movement of plunger 23 moves its associated switch element into circuit-closing or circuit-opening position.

In switches of the class described, an overrunning clutch arrangement renders the return upward movement of the plunger 23 inoperative to cause any further rotation of the switch element; thus the complete downward and return movement of the plunger 23 effects but one change in the electric circuit condition.

It is a feature of the present invention that the switch means are actuated simply by pressure on the lamp shade, such pressure causing a rotation of the lamp shade about a pivot point and a concomitant operation of the switch plunger 23.

To this end, the lamp shade 12 may be removably and pivotally supported on a central post 26, rigidly secured to the upper surface of the base 11, as shown in Fig. 3. The post 26 is advantageously formed of spring metal stampings of similar shape but of opposite hand, the stampings being configurated near the end portions thereof to cooperate in forming a suitable bearing having an outwardly flared mouth 27 through which suitable shade mounting means may be inserted into the bearing portion. It will be understood that the respective halves of the post 26 spread outwardly during the insertion of the shade, and snap into closed position to relatively snugly position the shade mounting means.

The shade 12 may be of any suitable design; the forms illustrated in Figs. 1 and 6 possess desirable artistic qualities, and structural advantages, as presently described.

The type of shade illustrated in Figs. 1 and 3 comprises a plurality of plates 30, 31, said plates being maintained in suitable spaced relationship by, suitable through pins and separators 32. Desirably the outer plates 30 are of transparent or translucent material, such as glass, molded plastic or the like, whereas the inner plates 31 may be of metal or other material which will form a pleasing contrast and artistic effect in combination with the material of the plates 30. In the embodiment of Fig. 3, the plates 31 have an inverted U shape, the central opening of the group of inner plates 31 forming a suitable hollow space for the accommodation of the electric lamp bulbs 14.

Suitably centrally positioned with respect to the shade elements 30, 31, there is provided a shaft 33 for cooperation with the central post 26 to effect the pivotal mounting of the shade 12. Shaft 33 may be secured to the outer shade elements 30 by screws 34, or equivalent. Said shaft is formed with a central preferably circular body 35, the extent of said circular portion being slightly greater than the width of the bearing portion of the supporting element 26. Enlarged terminal portions 36, see Fig. 2, serve

as stops to prevent lateral displacement of the shade with respect to its supporting post 26.

The innermost plates 31 of shade 12 may be provided, adjacent the ends thereof, with suitable rigid bearing elements 37, of metal, molded plastic, or the like, said bearing elements being positioned to overlie, and preferably contact with, the tips of the plungers 23. The location of the bearing provided in the post 26 with respect to the surface of base 11 provides for a substantially horizontal "normal" positioning of the shade 12 when the plungers 23 of the switches 15 are in fully extended position.

Therefore, after each oscillation of the shade 12 to actuate one or the other of the plungers 23, the reaction of the spring 24 of such operated plunger, in returning the plunger to its normal position, also serves to return the shade 12 to its "normal" position.

Referring now to the embodiments illustrated in Figs. 5 and 6, the lamp base 11 is desirably provided with interiorly disposed vertical wall members 40, said wall members being in suitable mutual spaced relationship and affording means for rigidly securing the switches 15, 15 in horizontal and mutually opposite position. The spacing of said walls 40, relative to the fully projected position of the switch plungers 23, 23 affords a spacing suitable for accommodating a tongue 41 fixedly secured, as by a pin 42, to the pivot member 33 of the lamp shade 12. In this embodiment of my invention, there are employed a pair of spaced supporting posts 26, secured to the surface of the base 11 in such manner as to provide a space for accommodating the tongue 41 at its point of securement to the shaft 35. The base 11 is formed with a suitable aperture 43 through which the tongue 41 may extend into the base 11.

As illustrated in Fig. 5, the shade 12 may comprise an upper plate 45, of transparent or translucent decorative material, disposed horizontally with respect to the base 11, as distinguished from the vertical arrangement of the respective plates in the embodiments of Figures 1 to 3, inclusive. The under plates 46 may be of metal, as aforesaid, and substantially annular, to afford a central opening sufficient to accommodate one or more bulbs 14, 14. For maintaining the plates 45, 46 in suitable spaced relationship, there are employed any suitable number of rivets 47 affixed to bosses 48 formed in the plate 45, and passing through suitably aligned holes in the plates 46. Each plate 46 has a downwardly struck fin 50, each fin serving to rest against the surface of the next lower plate 46 to suitably space the said plates. Thus, the rivet 47 may integrate the respective plates 45, 46 into the assembled shade 12.

In Fig. 7, a shade 12, generally of the type illustrated in Fig. 6, may be pivotally mounted for cooperation with one or more switches disposed, as in Fig. 1, near the end portions of the base 11, through the agency of a pair of downwardly extending flanges 55, 55 formed in the lowermost plate 46. Such flanges 55, 55 have formed therein, as by a suitable die operation, a pair of inwardly projecting bearings 56, said bearings arranged to cooperate with appropriate depressions formed in a post 57 which may be integral with the base 11, and which as is obvious, serves in substitution for the rigid post 26 of the embodiment of Fig. 3. By suitable configuration of the bearings 56, and the em-

ployment of yieldable flanges 55, the shade 12 may be readily removable from its supporting post 57.

The operation of the improved lighting fixture forming the subject of the present invention is illustrated in Fig. 1, the solid lines of said figure illustrating the normal horizontal position of the lamp shade, and illustrating its preferred relationship to the plungers 23 of the switches 13. As shown in broken line in Fig. 1, an oscillation of the shade 12 clockwise of Fig. 1 serves to depress the plunger 23 of the right-hand switch 13. Assuming the switch to have been in open circuit position, such plunger depression causes the switch to close the electrical circuit, and thus light its associated lamp 14. Upon release of pressure on the shade 12, the spring 24 of the switch operating element 23, in causing the return of the plunger to its normal position, also serves to rotate the shade counter-clockwise, returning it, also, to its normal position. Similarly, pressure exerted at the left hand of the shade of Fig. 1, causes the left-hand switch 23 to operate, either to light its associated lamp, or to extinguish it. In this manner, the respective lamps 14, 14 may be selectively controlled, by suitable oscillation of the lamp shade 12.

The embodiment illustrated in Fig. 5 operates in substantially similar manner. Pressure applied to either end portion of the shade 12 will cause an equivalent rotation of the shade about its pivot 33, and a rotative movement of the tongue 41, in a direction determined by which side of the shade is moved. The displacement of tongue 41 will exert a sideward pressure on either one or the other switch plunger elements 23. Upon release of pressure on the shade, the spring 24 of such plunger element serves to move the shade to its normal horizontal position.

From the wiring diagram illustrated in Fig. 4, it is apparent that either one or the other, or both, of the sockets 13 may be electrically connected to the power source 60, by the described operation of either, or both, of the switches 15.

As is well known in the art, standard switches of the type described are obtainable for controlling a plurality of electrical circuits. By the employment of such switches in connection with a pivotally mounted, oscillatable shade 12, a single switch may be employed for controlling a plurality of lamps 14.

Typical of other modifications or applications of my invention would be the complete disassociation of the switches 15 with respect to a common power source; for example one of the switches 15 may be in a standard lighting circuit, whereas the second might be installed in an emergency circuit or a circuit having electrical characteristics peculiar to a particular type of lamp 14. Such arrangement would provide for emergency lighting in the event that the normal power circuit were rendered temporarily inoperative. Other modifications of the electric circuit means may include the employment of a single lamp 14 of the double filament type, in which the filaments are under the respective control of separate switches 15; in other words any lamp of a type requiring two stages of switching operation may be employed pursuant to my invention.

Whereas I have described my invention by reference to specific forms thereof, it will be understood that many changes and modifications may be made without departing from the spirit of the invention.

I claim:

1. A lighting fixture including a base, a plurality of electric lamp means disposed thereon and arranged in a common electric circuit for individual or conjoint illumination, a lamp shade common to said lamp means, a member pivotally supporting said lamp shade, electric switch means for each of said lamps, means for operating said switch means, and means secured to said lamp shade for rotation therewith and engageable with the operating means of any one of said switches to actuate said switch operating means upon suitable rotation of said lamp shade.

2. A lighting fixture including a base, a plurality of electric lamp means disposed thereon, a lamp shade common to said lamp means and pivotally supported on said base at a point intermediate said lamp means, individual electric switch means for each said lamp means, spring-biased reciprocal means for operating said switch means disposed adjacent said lamp shade, and switch operating means attached to said shade for rotation therewith and adapted to actuate one or another of said spring-biased reciprocal switch operating means upon suitable rotation of said lamp shade.

3. A lighting fixture including a base, a plurality of electric lamp means disposed thereon, a lamp shade common to said lamp means and pivotally supported on said base at a point intermediate said lamp means, individual electric switch means for each said lamp means and rigidly mounted with respect to said lamp shade, spring-biased means for operating said switch means disposed adjacent said lamp shade, and rigid means secured to said lamp shade and normally in engagement with said switch operating means for actuating one or another of said switch operating means upon suitable rotation of said lamp shade.

4. A lighting fixture including a base, electric switch means fixed to said base, electric lamp means secured to said base and in electric circuit with said switch means for control thereby, a lamp shade, shaft means fixedly secured to said lamp shade, means engaging said shaft means for pivotally supporting said shade means upon said base, and a switch actuating member affixed to said shaft means for movement therewith, said switch actuating member being adapted to operate upon said switch means during rotation of said shade about its said supporting means to move said switch means into open or closed circuit position.

5. A lighting fixture including a base, electric switch means fixed to said base, a plurality of spaced electric lamp means electrically connected to said switch means, common shade means for said lamp means, horizontal pivot means for said shade means, spring means disposed on said base intermediate said lamp means for releasably receiving said lamp shade pivot means, and rigid means mounted upon said lamp shade and in engagement with said switch means for operation of said switch means upon rotation of said shade about said pivot.

6. In an electric lighting fixture, a support, electric lamps mounted thereon, fixedly mounted electric switch means for each of said lamps and in electric circuit therewith, said switch means having spring-biased actuating members, a normally horizontally positioned shade common to said electric lamps, means for pivotally mounting said shade about a horizontal axis to permit a rotation of said shade relative to said support,

and means connected to said shade and adapted to operate said switch means upon rotation of said shade, said spring-biased actuating members of said switch means operating upon said shade to return it to horizontal position after the rotation thereof.

7. A lighting fixture including a hollow base, a plurality of electric switch means rigidly disposed within said hollow base, electric lamp means disposed above said base and in electrical circuit with said switch means and controllable

thereby, shade means pivotally mounted with respect to said base, and a tongue secured to said shade means at the point of pivotal mounting thereof, said tongue extending into said hollow base and disposed intermediate said electric switch means and positioned to engage with either of said switch means to operate the same upon suitable displacement of said shade means about its said pivot.

EARL S. BOYNTON
